COFFEE GRINDER

Richard L. Schuhmann, Louisville, Ky., assignor to American Duplex Co., Louisville, Ky., a corporation of Kentucky

Application November 13, 1957, Serial No. 48,441

Term of patent 14 years

(Cl. D55—1)

The side of the coffee grinder not shown in Figure 1 is substantially like the side which is shown in said Figure 1.

The dominant features of my design reside in the portions shown in full lines in the drawing.

I claim:

The ornamental design for a coffee grinder, as shown and described.
